(57) **CLAIM**

The ornamental design for an electric pressure cooker, as shown and described.

DESCRIPTION

FIG. 1 is a front elevation view of an electric pressure cooker showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is a front perspective view thereof.

The broken lines shown in the drawings illustrate portions of the electric pressure cooker that form no part of the claimed design.
